(57) **CLAIM**

The ornamental design for an IC card type circuit module, as shown and described.

DESCRIPTION

FIG. 1 is a front elevation view of an IC card type circuit module showing our new design;

FIG. 2 is a left side elevation view thereof;

FIG. 3 is a top plan view thereof;

FIG. 4 is a right side elevation view thereof;

FIG. 5 is a bottom plan view thereof;

FIG. 6 is a rear elevation view thereof;

FIG. 7 is a top perspective view thereof; and,

FIG. 8 is a bottom perspective view thereof.
